(57) **CLAIM**

The ornamental design of a replaceable LED light source, as
shown and described.

DESCRIPTION

FIG. 1 is a perspective view of a replaceable LED light
source in accordance with the present invention.

FIG. 2 is another perspective view of a replaceable LED
light source in accordance with the present invention.

FIG. 3 is a front view thereof.

FIG. 4 is a rear view thereof.

FIG. 5 is a right end view thereof.

FIG. 6 is a left end view thereof.

FIG. 7 is a top view thereof; and,

FIG. 8 is a bottom view thereof.
